DESIGN FOR A SUIT

Virginia Gray, St. Louis, Mo.

Application February 19, 1941, Serial No. 99,109

Term of patent 3½ years

To all whom it may concern:

Be it known that I, Virginia Gray, a citizen of the United States of America, residing in the city of St. Louis and State of Missouri, have invented a new, original, and ornamental Design for a Suit, of which the following is a specification, reference being had to the accompanying drawing, forming part thereof.

Fig. 1 is a front view of a suit showing my new design.

Fig. 2 is a rear view thereof.

The body of the suit is comprised of an all over plaid fabric which is shown in part.

The characteristic feature of my design resides in the combination on the suit disclosed of the specific jacket member having wide braid trimming around the outer edges thereof, said trimming extending upward into the sleeves and center back, all as shown.

I claim:

The ornamental design for a suit, as shown and described.

VIRGINIA GRAY.
